United States Patent Office.

JOSEPH D. CARTER, OF THOMASTON, CONNECTICUT.

Letters Patent No. 67,495, dated August 6, 1867.

IMPROVED APPARATUS FOR STRAIGHTENING SHEET METAL.

The Schedule referred to in these Letters Patent and making part of the same.

TO ALL WHOM IT MAY CONCERN:

Be it known that I, JOSEPH D. CARTER, of Thomaston, in the county of Litchfield, and State of Connecticut, have invented, made, and applied to use a certain new and useful improvement in Straightening Rolled Sheet Metal; and I do hereby declare the following to be a full, clear, and exact description of the said invention, reference being had to the annexed drawing, making part of this specification, wherein—

Figure 1 is a vertical section of the machine employed by me for straightening sheets of rolled metal, and

Figure 2 is a plan of the same.

Similar marks of reference denote the same parts.

Sheet metal, when it is rolled, is seldom or never perfectly flat. It may be reduced to a perfectly uniform thickness, but it has an undulating surface, the undulations being generally at right angles to the motion of the sheets through between the rollers. This undulation is particularly detrimental in the sheets of brass employed for printers' rules, because said rules are entirely useless unless perfectly flat, and heretofore that condition could only be attained by costly and tedious manual labor.

My present invention relates to a method of flattening a sheet or strip of rolled metal, and is especially adapted to the flattening of sheets or strips of metal for printers' rules, but may be employed for any character of sheets of rolled metal.

The said invention consists in subjecting the sheet metal to a series of gradually diminishing bends between rollers or surfaces that act crosswise of the set or bend of the plate, and such bends acting alternately in opposite directions remove the previous set or bend of the plate, and gradually diminishing ultimately, leave the sheet perfectly flat.

In order to effect this straightening the more rapidly, I mount a series of bed-rollers, *a b c d e*, in a suitable frame, *f*, and fit the rollers *g h i k* in an adjustable frame, *l*, supported between standards *m*, and provided with set-screws *n* and *q*. The rollers in the frame *l* and the bed-rollers are to be geared together by a train of wheels, shown in fig. 2, and by dotted lines in fig. 1, each roller in the frame *l* coming above the space between two of the bed-rollers in *f*.

It will now be understood by the strip of sheet metal shown at *o*, in fig. 1, that the screws *n* and *q* are to be adjusted so that the strip of metal on entering receives a considerable bend between the rollers *a*, *b*, and *g*, and that the next rollers *g*, *b*, *h* bend the sheet in the opposite direction, but a less amount, and that the bends gradually diminish; and finally the rollers *d*, *k*, and *e* simply remove the slight bend left by the rollers *i*, *d*, *k*, leaving the sheet perfectly flat.

For the purpose of straightening sheet metal, I claim the arrangement of a series of rollers, in the manner described, by means of which a sheet of metal may be subjected to a series of gradually diminishing bendings, as set forth.

In witness whereof I have hereunto set my signature this thirteenth day of May, A. D. 1867.

JOSEPH D. CARTER.
